FIG. 1.

FIG. 2.

FIG. 3.

John Dean.

INVENTOR.

BY
Hubert E. Pick
ATTORNEY.

UNITED STATES PATENT OFFICE.

JOHN DEAN, OF RACINE, WISCONSIN.

COLLAR-FASTENER.

1,393,760.

Specification of Letters Patent.

Patented Oct. 18, 1921.

Application filed February 3, 1921. Serial No. 442,037.

To all whom it may concern:

Be it known that I, JOHN DEAN, a citizen of the United States of America, and a resident of Racine, county of Racine, State of Wisconsin, have invented certain new and useful Improvements in and Relating to Collar-Fasteners, of which the following is a specification.

This invention relates to certain improvements in apparel collar fasteners; and the objects and nature of the invention will be readily understood by those skilled in the art in the light of the following explanation of the accompanying drawings illustrating what I now believe to be the preferred mechanical expression or embodiment of the invention from among other forms, constructions and arrangements within the spirit and scope thereof.

It is not necessary herein to point out the objections against the use of collar buttons for attaching apparel collars at the back to shirt neck bands. These objections are too well known to need recitation herein.

It is an object of the present invention to provide means readily attachable to and removable from collars, whereby said collars can be easily fastened at the back to shirt neck bands and as readily detached therefrom, without employing the objectionable back or rear collar button and without utilizing the rear button hole of the shirt neck band.

With these and other objects in view, my invention consists in certain novel features in construction, arrangement and combinations as more fully and particularly pointed out and specified hereinafter.

Referring to the accompanying drawings: Figure 1 is a perspective view of a collar equipped with an embodiment of my invention, the neck tie being shown in the collar, all in readiness for attachment of the collar to the shirt neck band.

Fig. 2 is a vertical section taken at the rear of a collar attached to a shirt, showing the shirt neck band, and the device of my invention in operative position holding the collar down to proper position.

Fig. 3 is a view looking at the rear portion of the collar of Fig. 1, with the downward turned outer ply of the collar broken away to show the rear button hole of the collar and the embodiment of my invention applied to the collar as shown by Fig. 1.

Men's shirts without attached collars are

usually closed at the back and open at the front with the button holes at the front and back for the reception of collar buttons to secure the collar to the neck band at the front and back; the neck band being constructed and arranged at the back with a free lower longitudinal edge portion and a layer of fabric protecting the neck of the wearer from contact with the rear collar button, thus forming a pocket between said neck band and said layer of fabric with the pocket accessible at the rear of the shirt under said free edge portion of the neck band for insertion and removal of the rear collar button in and from said rear button hole, as is well understood by those skilled in the art.

My invention provides means attachable to a collar for utilizing said pocket (or the free rear lower edge portion of the neck band) for the attachment of the collar at the rear without the use of a rear collar button and the rear button hole of the neck band.

Whatever the form or construction of any embodiment of my invention (and my invention can be embodied in many various forms and constructions) said invention utilizes the rear button hole of the collar for removably anchoring the attaching device to the collar and provides a portion or member (thus anchored to the collar) to catch under said free lower edge of the neck band and extend up into said pocket to thereby anchor the collar to the rear of the neck band against upward movement of the collar with respect to the neck band, while the collar front ends are attached by the front collar button and the collar is thus held more or less closely to the neck band and against relative downward movement at the rear.

In the drawings, I show a common form of attachable collar 1 for a so-called open-front closed-back men's shirt 2, and in this collar, I show a necktie 3.

The collar is formed with the usual button holes 4 in its front ends or tabs, and with the usual rear collar button hole 5. It is common collar manufacturing practice, to locate the rear button holes 5 of all men's collars of this general type, a standard distance from the lower longitudinal edge of the collar.

The drawings show a portion of the shirt 2, having the neck band 6 with rear button

hole 7. The rear portion of the neck band is free at the lower edge 7^a and provides the common rear collar button pocket 7^b.

In the specific example of an embodiment 5 of the invention that is illustrated by the drawings, I provide a member 8 for threading through the collar button hole 5 and attaching the fastener to the collar, a member 9, to engage the shirt neck band and fit 10 within the collar button pocket 7^b thereof, and a tie or other suitable connection 10, securing the members, 8, 9 together. The member 8 as here shown is composed of thin 15 more or less flexible sheet material, such as celluloid, card board, or other suitable material.

In the example shown, the member 8, is thin, flat, longitudinally-elongated, and elliptical in form to facilitate threading 20 thereof through the button hole either end foremost, although I do not wish to so limit the broad features of my invention. Where the member 8 is thus formed to act as a button in threading through the button hole 25 5, I usually form the member of greater length than the button hole and of less width than the length of the button hole.

In the particular form shown, the member 30 9 is also thin and flat, composed of sheet material such as mentioned in describing member 8. However, I show the member 9 relatively large with respect to member 8 and of a form to fit in the neck band pocket against vertical tilting or so as to be confined 35 against dropping therefrom so long as the front ends of the collar are secured together and to the shirt by the front collar button. I happen to show the member 9 oblong in shape to provide longitudinal edge 9^a to engage 40 the top wall of the neck band pocket, and of a width to approximately equal the vertical depth of the neck band pocket. However, I do not wish to so limit the broad features of my invention.

45 In this example, I show member 9 tied to member 8 by a strong flexible connection such as a cord 10, which is here shown doubled or two ply, and attached to said members through the medium of transverse perforations therein. For instance, the member 8 is shown with perforations 8^a at its central portion through which the cord passes, while the member 9 has a perforation 9^b midway between its ends and located near 50 its longitudinal edge opposite edge 9^a. The cord can be passed through perforation 9^b and secured to member 9 by a slip noose, or in any other suitable manner.

The fastener is buttoned to the collar, *i. e.*, 60 is applied to the collar by threading the member 8 from the inside of the collar outwardly through the rear button hole 5 so that when adjusted to operative position, the member 8 will rest flat face against and 65 parallel with the surface of the collar that

faces or fits against the shirt neck band. The member 8 then covers the button hole 5 and the cord 10 extends rearwardly through said button hole and hangs therefrom within the collar and extends a short 70 distance below the collar with the member 9 hanging therefrom upside down, with respect to its operative position, as shown by Fig. 1. The necktie is inserted in the collar in the usual manner, and this can be done 75 either before or after the fastener is buttoned to the collar.

The collar is now in readiness for application to the neck of the wearer and for fastening to the shirt neck band. The collar containing the necktie and with the fastener applied and hanging as in Fig. 1, is placed around the neck and on the shirt neck band and the front ends of the collar are secured by the front collar button in the usual manner. The operator then fastens the collar at the back by swinging the member 9 upwardly and tucking the same into the collar button pocket of the neck band to the position illustrated by Fig. 2. The wearer can 80 easily reach one hand to the back of the collar and use the thumb to reverse the member 9 and tuck it up into said pocket. The operation is very simple and easily performed as the flexible connection 10 confines the 85 member 9 and serves as a hinge connection therefor, and yet holds the collar against riding up from the neck band after the member 9 has been tucked into the neck band pocket. When the collar is unfastened, at 90 the front for removal from the neck band, the member 9 is automatically removed from the pocket and detached from the shirt neck band, by the act of removing the collar from 95 the neck.

In fact, no special manipulation is required to detach the collar from the back of the neck band.

It will be noted that the members of the fastener are flat and do not obstruct the free 110 sliding movement of the necktie in the collar, nor does the fastener cause objectionable pressure against the neck of the wearer or an objectionable thickness of material at the back of the neck, and furthermore the fastener can be applied to collars and shirts as 115 now found on the market and does not necessitate changes in the structure thereof. While the fastener does not employ the rear button hole of the shirt neck band, yet the 120 rear button holes of the collar and neck band are in readiness to receive a collar button, should one of the fasteners of my invention be lost or not at hand. The length of the tie (cord 10) between the members 8, 9, can 125 be readily predetermined because of the known elevation of the collar button hole 5 above the lower edge of the collar, in practically all collars manufactured, and this length should be just sufficient to extend up 130

to and through button hole 5 and traverse the lower edges of the collar and neck band and allow for the swinging movement of the member 9.

5 It will be noted that my invention contemplates a fastener that is carried by the collar (whether or not of the particular construction illustrated) and provides end means to secure the fastener to the collar 10 through engagement with the rear button hole thereof and opposite end means to extend up into the neck band pocket to anchor the collar to the neck band, the intermediate portion of the fastener joining said 15 opposite end means and traversing the lower edges of the neck band and collar and extending up to the means engaging said button hole.

It is evident that various changes, variations and modifications can be resorted to 20 without departing from the spirit and scope of my invention, that the device can be used with other collars than that shown, all without departing from the spirit and scope of 25 my invention as defined by the claims, and hence I do not wish to limit myself to the exact disclosures hereof.

What I claim is:—

1. As an article of manufacture, a collar fastener constructed and arranged to be removably secured to and carried by the collar during application of the collar to and its removal from the shirt neck band, said fastener having a flat button for securing the 35 fastener to the collar through the rear button hole of the collar and provided with an anchor formed to extend up into the band pocket to anchor the rear of the collar against upward movement on the neck band, the intermediate portion of the fastener between said button and said anchor being 40 flexible and formed to extend down from said button and traverse the lower edge of the neck band.
2. A collar fastener embodying end means 45 to enter the rear button hole of the collar and thereby removably secure the fastener to the collar, opposite end means to removably extend up into the rear collar button pocket of the shirt neck band, and an intermediate flexible tie joining said opposite end

means and arranged to depend from the collar button hole and traverse the lower edges of the collar and neck band.

3. A collar fastener constructed and arranged to traverse the lower longitudinal edges of the collar and shirt neck band at the back and to extend up the collar to the rear button hole and at one end having swingable anchor means constructed and arranged to be swung upwardly and tucked up into the neck band pocket and at the other end having means to enter said button hole and thereby secure the fastener to the collar. 55

4. A collar fastener having means to button the fastener to the collar through the medium of the rear button hole of the collar, said fastener constructed and arranged to traverse the lower edges of the collar and neck band and provided with a flat sheet to extend up in front of the neck band and thereby anchor the rear of the collar against riding up on the neck band, said sheet being swingable with respect to the remainder 60 of the fastener. 65

5. A collar fastener consisting of a tie at one end having a member to button the fastener to the collar through the rear button hole and at the other end and having 70 a swingable member to fit up in the rear pocket of the shirt neck band. 75

6. A collar fastener consisting of a member adapted to be threaded through the rear button hole of a collar and to lie flat 80 against the collar, a flat member to removably fit within the rear pocket of a shirt neck band, and a flexible tie joining said members. 85

7. A collar fastener consisting of a flat 90 button member adapted to be buttoned to the collar through the rear button hole thereof, a flat member of sheet material adapted to be tucked up into the rear pocket of a shirt neck band, and a flexible connection 95 joining said members and of a length to extend up to said button hole and under the lower edges of the collar and neck band to the lower edge portion of said member extending upwardly in said pocket.

JOHN DEAN.
